UNITED STATES PATENT OFFICE

HARRY D. EISENHAUER, OF MOUNT RAINIER, MARYLAND

PIEZO-ELECTRIC CRYSTAL APPARATUS

Application filed March 21, 1927. Serial No. 177,190.

My invention relates broadly to piezo electric crystal apparatus and more particularly to a mounting for a piezo electric crystal element.

5 One of the objects of my invention is to provide a mounting for a piezo electric crystal element by which the condition of the oscillation of the piezo electric element may be facilitated.

10 Another object of my invention is to provide a piezo electric crystal holder wherein the piezo electric crystal element contacts with the bottom electrode of the holder solely through a central zone thereof leaving the 15 piezo electric crystal element free at opposite ends thereof for unrestricted oscillation along the Y axis.

Another object of my invention is to provide a piezo electric crystal holder in which 20 the friction between electrodes and the surfaces of a piezo electric crystal element is reduced to a minimum for facilitating the unrestricted vibration of the piezo electric crystal element for the development of constant 25 frequency electrical oscillations.

My invention will be more clearly understood from the following specification by reference to the accompanying drawings, in which:

30 Figure 1 is a plan view showing the piezo electric crystal holder; Fig. 2 is a cross-sectional view through the piezo electric crystal holder on line 2-2 of Fig. 1; Fig. 3 is a lateral cross-sectional view through the piezo 35 electric crystal holder on line 3-3 of Fig. 2 and Fig. 4 is a cross-sectional view through the piezo electric crystal holder on line 4-4 of Fig. 1.

The piezo electric crystal holder of my invention is particularly adapted for use with 40 low frequency piezo electric crystals, that is, crystals which oscillate at frequencies within a range of 10-100 kilocycles. I have found that low frequency crystals having a Y or 45 lateral axis vibration will not oscillate very readily when placed in a holder having the entire lower surface of the crystal in intimate contact with the lower metal contact plate or electrode. I have discovered that 50 this sluggishness is due to the friction which

exists between these surfaces when the crystal is oscillating. In the piezo electric crystal apparatus of my invention, I reduce the friction between the electrode and the surfaces of the piezo electric crystal element to a minimum allowing unrestricted vibration of the piezo electric crystal element along the lateral or Y axis thus increasing its piezo electric properties.

55 Referring to the drawings in more detail, reference character 1 designates the lower electrode of the piezo electric crystal holder. Reference character 2 represents an insulated housing which is positioned upon the lower electrode 1. A top closure 3 is provided for the insulated housing 2. The upper electrode 4 is secured to the top closure 3 by means of sets of screws or other suitable means 5. The upper electrode 4 is provided with a terminal 6 which passes through the top 3 for 60 establishing an electrical connection for the piezo electric crystal device exterior of the casing. Screw members 7 are provided for securing the upper portion 3 with respect to the lower plate 1. In order to center the 65 piezo electric crystal member 8 within the piezo electric crystal holder, I provide screw members 9 which engage screw threaded apertures in the lower plate 1. An eccentric device 10 may be provided on one of the end 70 screw members 9 and shifted in position for properly centering the piezo electric crystal member 8 while not restricting the free mechanical vibration thereof. The upper electrode 4 is centrally positioned over the piezo 75 electric crystal member 8 but is separated from the upper surface thereof by a positive air gap 11 allowing the free upper movement of the piezo electric crystal element 8 while 80 providing a capacitive connection with the upper surface thereof. The lower electrode 1 is provided with a central zone which I have indicated between the dimensions X-X which is in the nature of a plateau or high 85 flat surface in the center of the bottom electrode. This surface is substantially flat throughout the central zone and then tapers off in a plane represented at 12 and in a different plane represented at 13, these two 90 planes theoretically meeting at an apex at 95 100

substantially the center of the piezo electric crystal holder. By reason of the tapered off surfaces 12 and 13, a free air surface which I have represented at 14 is provided under the 5 ends of the crystal 8. This free air space 14 permits unrestricted oscillation of the piezo electric crystal element 8 along the lateral or Y axis, thus increasing the effective piezo electric crystal properties. The upper electrode 10 may rest on the crystal or may be separated by the air gap 11 which is approximately 3 to 5 thousandths of an inch. The upper electrode may rest upon the upper surface of the crystal and actually touch the upper 15 surface, but in this event, the central zone of the upper electrode is also in the form of a plateau tapering toward opposite ends of the piezo electric crystal holder.

By reason of the construction of the piezo 20 electric crystal holder as illustrated herein, piezo electric crystals may be made to oscillate which otherwise would not oscillate at all under any conditions or circumstances. I have found that by use of the present type 25 of piezo electric crystal holder that it has been possible to make two out of eight crystals oscillate with a type of holder where the contact electrodes are either in intimate contact or with one electrode spaced from one 30 surface of the piezo electric crystal whereas when the same crystals are placed in the holder of the present invention, all of the eight crystals produced sustained oscillations of constant frequency. I find that substantially 35 more output can be obtained when using the piezo electric crystal apparatus of my present invention than is possible in piezo electric crystal holders heretofore available in the art.

40 While I have described the crystal holder of my invention in one of its preferred embodiments, I desire it to be understood that modifications may be made and that no limitations are intended other than are imposed 45 by the scope of the appended claims.

What I claim as new and desire to secure by Letters Patent of the United States is as follows:

1. A piezo electric crystal holder comprising 50 a pair of electrodes, a piezo electric crystal, means for spacing one of said electrodes from one surface of said piezo electric crystal, the other of said electrodes having a flattened central zone and side zones 55 slightly inclined to said flattened central zone, said flattened central zone being adapted to contact with a surface of said piezo electric crystal.

2. A piezo electric crystal holder comprising 60 a pair of electrodes, a housing positioned upon one of said electrodes, means for supporting the other of said electrodes from said housing, a piezo electric crystal element, means for centering said piezo electric crystal element within said housing, said first men-

tioned electrode having a raised and flattened central zone for supporting said piezo electric crystal element out of contact with the surfaces of said electrodes on opposite sides of said flattened central zone.

3. A piezo electric crystal holder comprising 70 a pair of parallel electrodes, means on the lower of said electrodes for centering a piezo electric crystal element between said electrodes, a flattened central zone on said lower electrode for supporting said piezo electric crystal element substantially out of contact with the extremities of 75 said lower electrode on opposite sides of the flattened central zone thereof.

4. A piezo electric crystal apparatus comprising 80 a conductive base member, a housing carried by said base member, an upper electrode carried by said housing, a piezo electric crystal element located between said upper electrode and said base member, said base member being flattened in the central portion thereof and tapered on opposite sides of the flattened portion at substantially obtuse angles with respect to the plane of the flattened central portion thereof whereby said piezo electric crystal element contacts with said base member through a central zone thereof and is free to vibrate without restriction between said electrodes.

5. Piezo electric crystal apparatus comprising 90 a base member having a raised and flattened central portion, means disposed about the sides and at the ends of said base member for adjustably centering a piezo electric crystal element with respect to said base member with one face of said crystal element in contact with the raised and flattened central portion of said base member, a housing positioned on said base member, an electrode carried by said housing in spaced relation to the upper surface of said piezo electric crystal whereby said piezo electric crystal element is free to vibrate without restriction.

6. Piezo electric crystal apparatus comprising 100 a metallic electrode having a flat surface at its central portion and surfaces inclined with respect to and merging into said centrally disposed flat surface, said last mentioned surfaces of said electrode extending to the edges thereof, a piezo electric crystal supported upon said flat surface with portions of said piezo electric crystal element out of contact with the inclined surfaces of 110 said metallic electrode, a housing, a second electrode positioned within said housing for establishing a connection with the upper surface of said piezo electric crystal element whereby said piezo electric crystal element is free to vibrate without restriction between 120 said electrodes.

7. In a piezo electric crystal apparatus, a 115 housing, a lower electrode, an upper electrode, a piezo electric crystal element arranged to be centered between said electrodes and an ec- 125

centric member within said housing for adjusting the position of said piezo electric crystal element within said housing.

8. In a piezo electric crystal holder, an electrode having a centrally disposed plane flat surface and a plurality of surfaces merging into said first named surface but being slightly inclined thereto, said centrally disposed plane flat surface being adapted to contact with a surface of a piezo electric crystal.
